Homer H. Dasey
INVENTOR

BY
A. B. McCall
ATTORNEY

UNITED STATES PATENT OFFICE

91,421

DESIGN FOR A TOY DIVING SUBMARINE BOAT

Homer H. Dasey, Springfield, Ill., assignor to Dasey Boat Co., Springfield, Ill., a corporation of Illinois

Application May 31, 1933. Serial No. 48,252

Term of patent 3½ years

To whom it may concern:

Be it known that I, HOMER H. DASEY, a citizen of the United States, and a resident of the city of Springfield, county of Sangamon and State of Illinois, have invented a new, original, and ornamental Design for a Toy Diving Submarine Boat, of which the following is the specification, and reference being had to the accompanying drawing forming a part thereof.

submarine diving boat of my invention.

I claim:

The ornamental design for a toy diving submarine boat as shown.
